UNITED STATES PATENT OFFICE.

SOL S. SONNEBORN, OF BROOKLYN, NEW YORK.

TWIN-BAR SUSPENSION-INSULATOR.

1,337,284.

Specification of Letters Patent. Patented Apr. 20, 1920.

Application filed July 10, 1918. Serial No. 244,140.

To all whom it may concern:

Be it known that I, SOL S. SONNEBORN, a citizen of the United States, and a resident of Brooklyn, county of Kings, and State of New York, have invented certain new and useful Improvements in Twin-Bar Suspension-Insulators, set forth in the following specification.

This invention relates to strain insulators.

10 Its object is to produce a strain insulator less subject to breakdown than any heretofore produced.

In carrying out this general object I propose to combine with a pair of separated 15 terminals two or more connecting strips of insulating material, each or all of which are protected against the weather by a covering of molded insulating material.

Many further detailed objects of the invention are apparent from my specification.

The above will better be understood by reference to the illustrative embodiments described in detail in the following specification, which has reference to the accompanying drawings forming a part hereof, in which like characters designate corresponding parts. In the drawings—

Figure 1 is a vertical elevation, with parts shown in section, showing a series of 30 my insulators in accordance with my invention;

Fig. 2 is a horizontal section, with parts shown in plan, of one of my single insulator units; and

35 Fig. 3 is a vertical section corresponding in size to Fig. 2, showing one of my insulator units, parts of which are shown in elevation and parts broken away.

Heretofore many insulators have been 40 broken down needlessly because they have been subjected to strains far above what they could stand. Electrical engineers without difficulty can figure what an insulator unit or a series of insulator units can 45 withstand, but up to the present date no one has definitely prescribed the detailed specifications within which a string of high tension insulators should be safely employed.

50 It is a main object of my invention to provide a string of insulators including specially designed units, which may be employed with impunity, regardless of the potential difference placed upon the same 55 by their users.

More particularly it is an object of my

invention to provide a series of strain insulators of the type which support a conductor calculated to carry a potential of relatively great difference between it and ground. For this general object it is further an objective feature of my invention to provide an insulator unit which may be employed in series with a plurality of the same insulator units or with others. 65

Paying particular attention to one feature of my invention, an object is to provide in combination with an insulator a spark gap, the breakdown values of which are less than the ultimate breakdown between the terminals of the insulator with which it is associated. 70

Referring more particularly to the specific embodiment of my invention, an insulator unit is indicated by A. This unit comprises 75 two or more parallel spaced tension strips 1. In the embodiment there is illustrated a single pair of strips. Preferably these strips are formed of hydraulically compressed fiber or such material as is known 80 in the art as micarta. To reduce the tendency for surface leakage on account of the stratified character of this structure, the edges are interrupted by indentations 3. If desired the interruptions of the continuity 85 of the strata or fibrous continuity of these strips may be effected by transverse perforations as illustrated and described in my co-pending application, 757A, office docket.

Fundamentally, this application is applicable to an embodiment in which a pair or several connecting links of insulating material 1 are connected mechanically with separated terminals 4 and 5 by means of suitable cross-pins such as the cross bolt 6, 95 which centrally penetrates the eye 7 of the terminal 8.

It is preferred that an insulating bushing 9, which may be either of integral construction, as shown, or of concentric tubular construction, as desired, serves as the mechanical connecting means between the pin 6 and the links 1. 100

In the construction of each link, each terminal 8, which is preferably formed of conducting material such as malleable iron, has an eye 10, the interior of which is faced with an insulating bushing 11 of conducting material, which itself is preferably reinforced by a lining 12 of abrasive resisting material 110 such as copper, brass or plated sheet iron.

The insulated structure previously de-

scribed is preferably inclosed in a casing B of molded insulating material, which envelops the tension strips 1 and the terminals 10.

5 In many cases an insulator is subjected to electrostatic strain beyond its calculated limit. In this construction each terminal is provided with an electrical extension 20, which serve as connections for the horn 10 gaps C, which are preferably located vertically above the air space 21 intermediate the connecting links 1, so that in the event of an arc, the upward current of air through the space 21 directly across a gap C is serviceable in blowing out the arc.

Adjacent spark gaps C are preferably connected with conducting clips 22, attached to posts 20. These clips are obviously vertical in parallel to the flexible link connections 23, mechanically uniting two contiguous insulator units so that no electrical strain can exist between the eye of one insulator unit and the mechanically coupled eye of the next unit. This feature is beneficial in preventing puncturing through the insulators of the series.

The ground end of a string of my insulator units such as the string D of Fig. 1 is shown connected in an obvious manner with 30 a suitable support 24, through the medium of one of my connectors 23. It is preferred that the end 25 of the horn C adjacent ground be down into substantially electrical connection with ground, as indicated.

35 It should be noted that the horn gaps C are adjustable in the posts 20 through any suitable means such as the set-screw 26.

What I claim and what I desire to secure by United States Letters Patent is:—

40 1. In a system of strain insulator suspension, a ground; a string of one or more insulator units connected with said ground; each insulator unit comprising separated terminals and an insulating connecting link;

45 and grounded one or more series spark gaps, one for each said link.

2. A strain insulator comprising a pair of separated terminals of conducting material; a connecting link of insulating ma-

terial for said terminals; and a spark gap 50 bridging said link and connected at its ends with said terminals.

3. A strain insulator comprising a plurality of parallel tension strips of insulating material; a pair of separated terminals; and means insulated from said terminals for connecting said strips to said terminals.

4. A strain insulator comprising a separated pair of parallel strips of insulating material; a pair of separated terminals; and 60 insulated means connecting said strips and said terminals.

5. An insulator comprising two separated metallic terminals; an insulating link means connecting said terminals and providing a 65 vertical opening; and a spark gap connected with said terminals and located directly above said opening.

6. A high potential insulator comprising two conducting terminals and a body of insulating material having an opening forming a duct for the passage of air; and spark-gap elements connected with said terminals and located so that said spark gap is subject to the flow of air through said duct. 70

7. A series of strain insulators mechanically connected between a support and a conductor and inherently constituting zones of greater and less insulating value; and a circuit including spark gaps paralleling 80 said series with one spark-gap opposite each said insulating portion of greater value and terminally connected between said support and said conductor.

8. A series of strain insulators for line 85 support, each comprising separated insulating links adapted to lie in a horizontal position so that an upward flow of air is permitted between said links; and a series of spark-gaps one for each insulator connected 90 in parallel with said insulators so that each said spark-gap protects an insulator of the series.

In testimony whereof I have signed my name to this specification, this 14th day of 95 May, 1918.

SOL S. SONNEBORN.
